UNITED STATES PATENT OFFICE

120,049

DESIGN FOR A BOTTLE HOLDER

Herbert Rubin, Brooklyn, N. Y.

Application January 26, 1940, Serial No. 89,753

Term of patent 7 years

To all whom it may concern:

Be it known that I, Herbert Rubin, a citizen of the United States, residing at 50 Plaza Street, Brooklyn, in the county of Kings and State of New York, have invented a new, original, and ornamental Design for a Bottle Holder, of which the following is a specification, reference being had to the accompanying drawing, forming part thereof.

I claim:

The ornamental design for a bottle holder, substantially as shown.

HERBERT RUBIN.
